UNITED STATES PATENT OFFICE.

GEORGE F. BROCKWAY, OF EDEN TOWNSHIP, FAYETTE COUNTY, IOWA.

RAILWAY-TIE.

1,176,029.

Specification of Letters Patent.

Patented Mar. 21, 1916.

Application filed November 19, 1915. Serial No. 62,322.

To all whom it may concern:

Be it known that I, GEORGE F. BROCKWAY, a citizen of the United States, residing at Eden township, in the county of Fayette 5 and State of Iowa, have invented new and useful Improvements in Railway-Ties, of which the following is a specification.

This invention relates to the cross ties which support the rails of railway tracks, 10 and more particularly to ties which are constructed of metal.

The invention has for its object to provide a metallic tie of novel form and construction, whereby great strength and durability 15 are obtained, and at the same time a cushioned support for the rails is had.

The invention also has for its object to provide a tie of the kind stated which is firmly held in place on the road bed, and is 20 effectually prevented from shifting in the direction of the length of the track or sideways thereof.

With the objects stated in view, the invention consists in a novel combination and arrangement of parts to be hereinafter described and claimed, and in order that the same may be better understood, reference is had to the accompanying drawings, in which—

30 Figure 1 is a plan view of the invention; Fig. 2 is a side elevation, partly in section, on the line 2—2 of Fig. 1; Fig. 3 is a cross-section on the line 3—3 of Fig. 1, and Fig. 4 is a cross-section on the line 4—4 of Fig. 1.

35 Referring specifically to the drawing, the tie is composed of a top metallic plate 10 and a bottom metallic plate 11 below the same. These plates are separate, and spaced so that a cushioning block 12 of wood or other suitable material may be interposed therebetween. The cushioning members do not extend throughout the entire length of the tie but are only at the rail-engaging ends thereof, thereby effecting a saving of wood or 45 other material used for the cushioning members.

At the longitudinal edges of the top plate 10 are continuous, integral downturned flanges 13, and similar flanges 14 are at the 50 longitudinal edges of the bottom plate 11. These flanges lap sufficiently to prevent the plates from shifting laterally relative to each other, and they also assist to hold the cushioning members 12 in place, the same 55 fitting between the flanges 13.

At the longitudinal center of the bottom plate 11 is an integral depending vertical flange 15 having at the bottom outstanding flanges 16 extending in opposite direction from the respective sides of the flange. The 60 depending flange is therefore of inverted T-form and its function is to anchor the tie in the roadbed and prevent the same from creeping in the direction of the length of the track. The flanges 14 also assist to prevent 65 creeping of the tie in this direction. It will be understood, of course, that when the tie is in place, the flanges 14 and 15 are embedded in the road bed.

The rails of the track are indicated at 17, 70 they being secured to the tie by inner and outer clamping members 18 and 19, respectively, engaging the base flanges of the rail.

The inner rail-clamping members 18 are secured to the top plate 10 of the tie by 75 bolts 20, and the outer rail-clamping members 19 are each secured by a U-bolt 21. These U-bolts pass under the flanged bottom of the flange 15, and upward on opposite sides thereof, and through the plates 10 and 80 11, as well as through the cushioning members 12, thereby holding the latter in place. The upper ends of the U-bolt shanks pass through the clamping members 19, and rise 85 therefrom a sufficient distance to receive 85 nuts 22, which are screwed down against the top of said clamping members.

The bottom of the plate 11 has transverse webs 23 having recesses 24 in their outer vertical edges which form seats for the 90 shanks of the U-bolts 21. These webs extend between the bottom of the plate 11 and the sides of the flanges 15, and serve to lend added strength to the structure, and also to prevent the tie from shifting in the 95 direction of its length.

Where a joint between rails 17 occurs, a fish plate 25 is provided, the same being secured by the nuts 22.

The plates 10 and 11 are clamped together 100 midway between their ends by a U-bolt 26 arranged in the same manner as the U-bolt 21. This portion of the plate 11 has a bottom web 27, the same as the webs 23, and also provided with seats for the shanks 105 of the U-bolt 26. The U-bolt 26 is secured by nuts 28 screwed down on the top plate 10, and held by a nut lock-plate 29 seating on top of the plate 10, and having apertures 110 30 in which the nuts seat, whereby they are

prevented from turning off the U-bolt shanks. The plate 29 extends across the plate 10, and has downturned ends 31 engaging the flanged sides of said plate and the bottom of the flanges 13 and 14.

The structure herein described provides a strong and durable metallic tie, and also one which gives the rails a cushioned support. The cushioning member 12 can be readily removed for renewal by simply removing the U-bolts 21. The tie provides a wide bearing for the rails, thereby reducing end wear on the rails to a minimum.

I claim:

- 15 1. A metallic railway tie, comprising spaced top and bottom plates, cushioning members held between the end portions of the plates, and a depending longitudinal flange on the bottom of the bottom plate, said flange having oppositely extending out-standing bottom flanges.
- 20 2. A metallic railway tie, comprising spaced top and bottom plates and cushioning members held between the end portions 25 of the plates, the bottom plate having continuous depending flanges at its longitudinal edges.
- 30 3. A metallic railway tie, comprising spaced top and bottom plates, cushioning members held between the end portions of the plates, the bottom plate having continuous depending flanges at its longitudinal edges, and a depending longitudinal flange on the bottom of the bottom plate, said

flange having oppositely extending out-standing bottom flanges.

4. A metallic railway tie, comprising spaced top and bottom plates, cushioning members held between the end portions of the plates, the bottom plate having continuous depending flanges at its longitudinal edges, a depending longitudinal flange on the bottom of the bottom plate, and transverse webs between the bottom of the bottom plate and the sides of the aforesaid flange. 40 45

5. A metallic railway tie, comprising spaced top and bottom plates, cushioning members held between the end portions of the plates, a depending longitudinal flange on the bottom of the bottom plate, and 50 U-bolts passing under said flange and having its shanks extending through the plates and the cushioning members therebetween.

6. A metallic railway tie, comprising spaced top and bottom plates, cushioning members held between the end portions of the plates, a depending longitudinal flange on the bottom of the bottom plate, U-bolts 55 passing under said flange and having its shank extending through the plates and the 60 cushioning members therebetween, and transverse webs between the bottom of the bottom plate and the sides of the flanges, said webs having edge recesses in which the 65 U-bolt shanks seat.

In testimony whereof I affix my signature.

GEORGE F. BROCKWAY.
